UNITED STATES PATENT OFFICE.

WILLIAM B. HAMILTON, OF HYDE PARK, ILLINOIS, ASSIGNOR TO JESSIE M. HAMILTON, OF SAME PLACE.

LOCK-BOX COVER.

SPECIFICATION forming part of Letters Patent No. 225,123, dated March 2, 1880.

Application filed December 5, 1879.

To all whom it may concern:

Be it known that I, WILLIAM B. HAMILTON, of Hyde Park, in the county of Cook and State of Illinois, have invented certain new and useful Improvements in a Lock-Box Cover for Shut-Off Cocks on Water and Gas Pipes; and I do hereby declare that the following is a full, clear, and exact description thereof, which will enable others skilled in the art to which my invention appertains to understand and make use of the same, reference being had to the accompanying drawings, and to letters of reference marked thereon, which form a part of this specification.

15 Figure 1 is a view, looking from above, of a box-top with the cover closed; Fig. 2, a view of the same with the hinged cover thrown open, showing the arrangement of my improved locking device; Fig. 3, a vertical cross-section in the plane $x-x$, Fig. 1; and Fig. 4, a vertical cross-section in the plane $y-y$, Fig. 2.

The object of this invention is the construction of an improved device for securing or locking the tops or covers of the street-boxes 25 inclosing the shut-off cocks of water and gas pipes, the exact arrangement and construction of which will hereinafter be more fully explained in detail.

Heretofore corporations have been greatly annoyed by mischievously-disposed persons, and more especially children, opening the loose covers of these street-boxes and filling them with all kinds of convenient débris, and which, as a matter of necessity, had to be removed, requiring considerable time and labor for that purpose, and often causing considerable damage on account of the street-boxes being filled up with dirt, thereby preventing the immediate closing of the shut-off cock. By 40 the employment of the simple and convenient device herein shown a great amount of labor and expense is saved.

Referring to the drawings, A represents the ordinary cast-iron box-top embodying my improvement, which forms the top of the street-box, inclosing the shut-off cock; and B, the cover to the same.

C represents a latch capable of being rotated, and is attached to the under side of the

cover B by means of the vertical stem a, which 50 extends upward through the cover B, as shown in Fig. 1 of the drawings.

The stem a, as herein shown, is formed with square ends, the lower end forming the axis for the movement of the latch C, and the upper end coming up on a level with the outside surface of the cover B, the parts surrounding the upper end of the stem a being cast with a countersink or depression, in order to admit of a hollow key or socket-wrench engaging 60 with the stem a, for the purpose of locking and unlocking the cover B.

Formed integral with the latch C, and extending upward therefrom, is a pivot point or projection, D, which, when the parts are locked 65 together, engages with the under side of the lip-like projection a', which is cast on or attached to the inside of the box-top A, as shown in Fig. 4 of the drawings. The under surface of the lip a', with which the pivot-point D is 70 made to engage, has an oblique angle in relation to the square of the box-top, as shown in Fig. 4 of the drawings, adapting the locking parts to wedge together.

By having a small or pivot point projecting 75 at right angles from the latch C, instead of a large or flat surface, and the under side of the lip a' being wedge-shaped, the locking parts are not so liable to be affected by rust and become stuck together.

The stem a should be made of brass or other material not subject to corrosion, and all the locking parts may be composed of similar material, should practical working so require.

I do not confine or limit myself to the construction of a square end for the operating-stem of the locking parts, but may adopt any other shape or form that will require a peculiar-shaped key or wrench to operate the same.

Having thus described my invention, what I 90 claim as new, and desire to secure by Letters Patent, is—

1. In a lock-box cover, the lip-projection a', having the under side or bearing-surface thereof at an oblique angle relative to the square 95 of the box A, in combination with the pivot or conical locking-point D, constructed integral with the latch C and projecting upward at

right angles therefrom, adapting the same to engage with the under side of the lip a' , as herein set forth.

2. The combination, with the operating-stem a and the latch C , provided with the conical locking-point D , of the lip-projection a' , having the under side or bearing-surface set at an

oblique angle relative to the impinging-point D , and the box-top A , arranged and operating as and for the purpose set forth.

WILLIAM B. HAMILTON.
